Attorney

UNITED STATES PATENT OFFICE.

JAMES J. HOLLAND, OF PHILADELPHIA, PENNSYLVANIA, ASSIGNOR OF ONE-HALF TO
GEORGE H. KILLIAN, OF PHILADELPHIA, PENNSYLVANIA.

ATOMIZER.

1,229,615.

Specification of Letters Patent. Patented June 12, 1917.

Application filed August 15, 1916. Serial No. 115,038.

To all whom it may concern:

Be it known that I, JAMES J. HOLLAND, a citizen of the United States, residing at Philadelphia, in the county of Philadelphia and State of Pennsylvania, have invented 5 certain new and useful Improvements in Atomizers, of which the following is a specification.

My invention relates to improvements in 10 atomizers, the object of the invention being to provide an atomizer which can be cheaply manufactured, so that it can be sold at an unusually low price and yet most efficiently perform the functions for which it is intended.

A further object is to provide an atomizer 15 in which the air tube and liquid tube are secured in a sheet metal shell, punched or otherwise shaped, and providing a strong support for the tubes.

A further object is to provide an improved construction of shell operating as, or in conjunction with, a stopple, closing the open end of a bottle or receptacle.

With these and other objects in view the 25 invention consists in certain novel features of construction and combinations and arrangements of parts as will be more fully hereinafter described and pointed out in 30 the claims.

In the accompanying drawings:

Figure 1 is a view in vertical section, illustrating one form of my invention.

Fig. 2 is an enlarged fragmentary view 35 in transverse section on the line 2-2 of Fig. 1, and

Fig. 3 is a view similar to Fig. 1, illustrating a modification.

1 represents a bottle having the ordinary 40 tapering neck 2. 3 is the shell or casing of my improved atomizer which has its lower reduced end 4 secured within a hollow stopple 5, although, of course the shell itself may fit the bottle, but in most cases it is 45 desirable to provide a thickness of material around the shell, of cork, glass, or any other suitable material which will snugly close the neck of the bottle.

A cap 6 having a flange 7 at its edge, is 50 secured on the open end of the shell in any approved manner, and may be printed, embossed, or ornamented in any approved manner.

8 represents a liquid tube which extends

through the bottom 9 of shell 3 and through 55 the side of shell 3 and is preferably secured at both points by solder 10. 11 represents an air tube which extends through one side wall of the shell as shown at 12 and is likewise secured by a drop of solder 10. 60

Nozzle 13 is provided at the outlet end of air tube 11 and is made with a slightly tapering nipple 14 which projects through an opening 15 in the wall of shell 3 and into the end of tube 11, and a drop of solder 65 10 operates to securely hold the parts together, although there is considerable frictional engagement and binding action.

The nozzle 13 has a longitudinal passage 16 of approximately the bore of tube 11 70 but in its extreme outer end is provided with a restricted orifice 17, through which the air is ejected in a fine stream with sufficient pressure to suck the liquid up through the tube 8 and atomize the same.

While of course, air may be forced in any 75 approved manner through the air tube, I have shown an ordinary bulb 18 connected by a hose 19 with one end thereof.

To prevent a partial vacuum in the bottle 80 1, vent holes 20 are provided in cap 6 and bottom 9.

In the modification illustrated in Fig. 3, I provide a shell 21 which constitutes a cap fitting over the open end of bottle 23. In 85 this modification, the liquid tube 24 extends only through the side of shell 21, but the air tube 25 corresponding to air tube 11, is secured in precisely the same manner as the preferred form.

In the modification, I also use solder indicated at 10 to secure the tubes in the shell, and I have shown an air bulb 26 directly connected to the air tube.

With both forms of my invention, the 90 shell can be stamped or punched from sheet metal, and the tubes can be rigidly secured without the necessity of expensive machine work.

I have dispensed altogether with the use 100 of screw-threaded parts, and have provided a most efficient atomizer which can be manufactured at an extremely low cost.

Various slight changes may be made in the general form and arrangement of parts 105 described without departing from my invention and hence I do not limit myself to the precise details set forth, but consider

myself at liberty to make such changes and alterations as fairly fall within the spirit and scope of the appended claims.

Having fully described my invention, 5 what I claim as new and desire to secure by Letters Patent is:

1. An atomizer, comprising a shell, a liquid tube projecting through one side wall of the shell, and having its outlet end outside 10 of the shell, an air tube projecting through one wall of the shell, and a nozzle secured to the other wall of the shell and to the air tube and directing the air across the outlet end of the liquid tube.
- 15 2. An atomizer comprising a shell, a liquid tube projecting through the shell and secured thereto, an air tube projecting through one wall of the shell, a nozzle projecting through the other wall of the shell and secured in the air tube, said nozzle having a restricted orifice adjacent the outlet end of the liquid tube.
- 20 3. An atomizer comprising a shell, a liquid tube projecting through one wall of the shell, an air tube projecting transversely of the shell, a nozzle having a tapering end projecting through the shell and into the

end of the air tube and solder securing said tubes and nozzle to the shell.

4. An atomizer comprising a shell, said shell adapted to be positioned in the open end of a receptacle, a liquid tube projecting through the bottom and one side of said shell, an air tube located transversely of the shell and having its discharge end located in proximity to the outlet end of the liquid tube, a cap secured on the open end of the shell and vent openings in said cap and in the bottom of the shell.

5. An atomizer comprising a hollow shell 40 having a reduced lower end, a hollow stopple secured around the reduced end of the shell, liquid and air tubes secured in the shell, and projecting through the side wall thereof above the stopple, and a cap secured over the open end of the shell.

In testimony whereof I have signed my name to this specification in the presence of two subscribing witnesses.

JAMES J. HOLLAND.
